(57) **CLAIM**

The ornamental design for a handbag, substantially as shown and described.

DESCRIPTION

FIG. 1 is a perspective view of a first preferred embodiment of the design of the present invention as it would appear with the top portion not spread apart;

FIG. 2 is an elevation view of one side of a first preferred embodiment of the design as shown in FIG. 1, the other side being the mirror image thereof;

FIG. 3 is a front elevation view of a first preferred embodiment of the design as shown in FIG. 1;

FIG. 4 is a rear elevation view of a first preferred embodiment of the design as shown in FIG. 1;

FIG. 5 is a top elevation view of a first preferred embodiment of the design as shown in FIG. 1;

FIG. 6 is a bottom elevation view of a first preferred embodiment of the design as shown in FIG. 1;

FIG. 7 is a side elevation view of the a first preferred embodiment of design as it would appear with the top portion spread apart, the other side being the mirror image thereof; and,
FIG. 8 is a top elevation view of the first preferred embodiment of design as it would appear with the top portion spread apart;

In all Figures, the light stippling is intended to indicate a fabric material.

In FIGS. 1-8 showing the first preferred embodiment of the design, the non-stippled front and bottom panels are intended to indicate leather or leather-like material.
